ELECTRON MULTIPLIER

George Baldwin Banks, Chelmsford, England, assignor to Radio Corporation of America, a corporation of Delaware

Application August 31, 1937, Serial No. 161,731
In Great Britain June 26, 1936

4 Claims. (Cl. 250—27.5)

This invention relates to electron multipliers in which an electron multiplication effect is obtained by secondary emission, the number of electrons in a primary stream being increased by bombardment of a secondary emitter electrode which emits a number of secondary electrons greater than the number of impinging electrons. As is known, electron multiplication upon this principle may be effected in almost any desired number of stages, very large amplification of an original electron stream being thus possible. Electron multipliers of the magnetic type as disclosed, for example, in United States Patent 2,078,304, Zworykin et al., April 27, 1936, utilize a row of secondary electron emitter electrodes situated in one plane, a row of electrostatic field electrodes situated in a parallel plane, a primary cathode at one end and an output electrode near the other end of the row of secondary emitters, and a magnetic field in the space between the two rows of electrodes. Such devices, especially when multi-stage, require rather high applied unidirectional operating potentials in order to obtain the necessary potential gradient between the emitters, and, as a rule, a large number of external connections must be provided through the envelope of the device.

The object of the present invention is to provide an improved electron multiplier which has a minimum of external connections and for which relatively low operating potentials are sufficient.

In accordance with the invention the unidirectional electrostatic fields used in the known types of electron multipliers are replaced by high frequency alternating electrostatic fields obtained through connections such that alternate secondary emitters are connected in a group in which all emitters are of one instantaneous polarity, the remaining secondary emitters in another group in which all emitters are of the other instantaneous polarity, and the instantaneous polarity of each field electrode is the same as that of the secondary emitter electrode which is next the emitter directly opposite the field electrode in question. Preferably, the alternate electron emitters of one group are connected together within the envelope to one external connection lead, the remaining alternate electron emitters of the other group are connected together within the envelope to another external lead, and alternate field electrodes are also connected within the envelope to form two groups of connected electrodes so that all of the field electrodes in each group are of the same instantaneous potential as one another and as the corresponding group of

emitters. With this arrangement, and if the device has a photoelectric, as distinct from a thermionic primary cathode, only three external connections are necessary, one to the output electrode, and the others to the two external terminals by which the high frequency alternating potential is applied to the two cooperating groups of emitters and of field electrodes.

One embodiment of the invention is shown diagrammatically in the accompanying drawing, 10 which shows an electron discharge device having an evacuated cylindrical or other suitably shaped bulb or envelope B enclosing an emitter of primary electrons, such as a photocathode E—1, a plurality of secondary electron emitters E—2 to E—7, 15 of any known type, such as caesium coated electrodes, a plurality of field electrodes F—9 to F—15, and an output anode A. The photoelectric cathode and the six secondary emitters are arranged side by side in the same plane with one another to form a row of seven electron emitters with the primary emitter at one end, the output anode B being mounted near the other end. The seven field electrodes are mounted side by side to form a row of field electrodes in a plane parallel to the plane of the row of emitters. The first field electrode F—9 is opposite and faces the primary cathode and each of the other field electrodes is opposite and faces a corresponding secondary emitter.

The first field electrode and the primary cathode form a pair of opposed spaced electrodes, one of which is an electron emitter, and the other field electrodes and the secondary emitters form six other similar pairs of electrodes. These pairs of electrodes mounted side by side form two rows of electrodes in parallel planes. Any odd number of such pairs may be used, the drawing showing seven pairs, which is a convenient number of stages. The output anode is a plate at right angles to the planes of the rows of emitters and field electrodes, and is situated at the end remote from the primary cathode, facing toward the space between the two planes.

A magnetic field extending between and transverse to the rows of electrodes in a plane parallel to the planes of the electrodes is produced by a magnet M which may conveniently be constructed and mounted as shown in the above mentioned United States Patent 2,078,304.

Although the tube is operated with a rather low alternating potential instead of with the rather high unidirectional potential generally used for electron multipliers, the multiplication is obtained in much the same manner as in the

prior electron multipliers, as the electrons from the first emitter flow along a curved path to the second emitter where secondary electron multiplication occurs, the secondary electrons from the second emitter flow along a curved path to the third emitter, where further multiplication takes place, and so on until the output electrode is reached.

In accordance with the invention there is impressed on the rows of emitters and field electrodes an alternating potential high enough to cause the electrons to flow from one emitter to the next and produce multiplication, and of a frequency such that the period of each half cycle is substantially the same as the transit time of an electron moving from one emitter to the next. In order to obtain the successive multiplications with an alternating operating potential every other emitter and every other field electrode is connected to one pole of the alternating voltage source, and the remaining emitters and field electrodes are connected to the other pole. As indicated in the drawing, the first, third, fifth, and seventh emitters, that is, the primary emitter 25. E-1 and the secondary emitters E-3, E-5, and E-7, are connected to one another and also to the second, fourth, and sixth field electrodes F-10, F-12, and F-14, by connections of negligible impedance preferably within the envelope, comprising wires W between the emitters and the field electrodes and a connector or wire L-1 joining the emitters and extending through the wall of the envelope to an external terminal T-1. The second, fourth, and sixth emitters, that is 30 E-2, E-4, and E-6, are connected through wires W to the first, third, and fifth electrodes F-9, F-11, F-13, and also to one another and to the seventh or last field electrode F-15 by a wire or connection of negligible impedance L-2, which extends through the wall of the bulb to a second external terminal T-2. Each field electrode, except the last one, is connected by a wire W to the emitter next to that emitter which is opposite the field electrode, so that field electrodes F-9 to F-14 are connected to emitters E-2 to E-7 respectively. A source S of alternating voltage, of high frequency, for example from 50 to 100 megacycles, has its opposite poles connected to the external terminals T-1 and T-2. The output anode A is connected to one of the terminals, through a load impedance O and a battery or similar source of potential D having its negative terminal grounded.

The operation of the device is as follows:

When light falls on the primary emitter or photocathode E-1, primary electrons are emitted. On the first half cycle of the alternating operating voltage the first field electrode F-9 and the second emitter E-2 become positive with respect to the primary cathode, and the primary or photo-electrons travel in more or less curved paths to and impinge on the second emitter E-2, causing secondary electron emission. The frequency and amplitude of the high frequency voltage wave applied to the terminals T-1 and T-2 are so chosen that the transit time of the electrons from each emitter to the next is equal to one-half cycle of the impressed voltage, consequently at the moment of impact of the primary electrons on the second emitter E-2 at the end of the positive cycle, that emitter and the first field electrode F-9 are just reversing in instantaneous polarity. During the next or second half cycle both the next or third emitter E-3 and the second field electrode F-10 be-

come positive with respect to the second emitter E-2, so that secondary electrons emitted from the second emitter E-2 are drawn away by the positive field electrode F-10 and move toward the next or third emitter E-3 in approximately 5 similar curved paths. On reversal in polarity during the third half cycle the secondary electrons from the third emitter E-3 similarly move to the fourth emitter E-4, and so on, along the length of the discharge device, until the output anode is reached, the electron stream being multiplied at each impact.

Although the potential of the second emitter E-2 is zero at the time the primary electrons reach it, the electrons have a velocity equivalent 15 to that acquired by an electron falling through a potential gradient somewhat more than half the peak amplitude of the oscillatory field. As a result, electrons arriving at, or shortly after, the moment when the emitter is changing polarity, will impinge on the emitter and produce secondary electrons, which will be drawn off. As with all multipliers of the oscillatory field type the first action is one of minification because electrons can leave the photocathode only during the 20 half cycle when the first field electrode and first emitter are positive with respect to it. During the other half cycle the electrons cannot leave the cathode. As only those electrons which are emitted during the first 60° of the favorable half 30 cycle will arrive at the first emitter under favorable conditions for multiplication, only a fraction of the primary photoelectrons leave the cathode under favorable conditions, but all of the electrons constituting this fraction will reach 35 the first secondary emitter at a moment and under conditions suitable for the emission of secondary electrons, and similarly, these secondary electrons will find conditions favorable for multiplication during their passage through the 40 device.

It is evident that with the above described arrangement there is no need for any very high potential supply, as the oscillatory electrostatic field may be of comparatively low amplitude, and furthermore, the number of external connections is reduced to three only.

I claim:

1. An electron multiplier comprising an evacuated envelope enclosing a row of discrete electron emitters in one plane, a row of corresponding discrete field electrodes mounted in a parallel plane and each opposite an emitter, an output anode adjacent the last emitter and the last field electrode in said rows, a connector of negligible impedance inside said envelope between the first emitter and each alternate emitter in the row, a second connector of negligible impedance inside the envelope between the second emitter, each alternate emitter in the row, and the last field electrode, each of said connectors extending through the wall of said envelope to form an external terminal, and means inside said envelope conductively connecting each field electrode except the last to the emitter next to and further away from the first emitter than the emitter opposite said field electrode.

2. An electron multiplier comprising two rows of the same odd number of discrete opposed electrodes mounted in spaced parallel planes, an anode at one end of said rows of electrodes, two connections of negligible impedance inside said envelope and extending from all said electrodes through the wall of the envelope to two external terminals, the alternate electrodes in each row

as counted from the same end being connected by one of said connections to cause the odd number electrodes in the first row and the even number electrodes in the second row all to be maintained at the same instantaneous potential and by the other of said connections to cause the even number electrodes in the first row and the odd number electrodes in the second row all to be maintained at the same instantaneous potential.

3. An electron multiplier comprising an evacuated envelope enclosing an odd number of discrete electron emitters mounted in a row in the same plane, the first emitter in the row being a primary electron emitter, an equal number of discrete field electrodes mounted in a row in a plane parallel to the plane of the row of emitters with each field electrode opposite an emitter, an output anode adjacent the last emitter and the last field electrode in said rows, one connection of negligible impedance inside said envelope connecting and thereby maintaining at the same instantaneous potential the first and each alternate emitter and the second and each alternate field electrode, said connection extending through the wall of said envelope to provide an external

terminal, and a second connection of negligible impedance inside said envelope connecting and thereby maintaining at the same instantaneous potential the second and each alternate emitter and the first and each alternate field electrode, said second connection extending through the wall of the envelope to provide a second external terminal. 5

4. An electron multiplier comprising an evacuated envelope enclosing an odd number of discrete pairs of spaced opposed electrodes mounted side by side to form two rows of electrodes in parallel planes, one electrode of each pair being an electron emitter and the other a field electrode, means for producing a magnetic field between and transverse to said rows and parallel to the planes of said rows, an output anode adjacent one end of said rows of electrodes, a conductive connection including an external terminal connecting all of the even number emitters 10 and all of the odd number field electrodes except the last, and a second connection including another external terminal connecting all of the odd number emitters and all of the even number field electrodes. 15 20 25
